UNITED STATES PATENT OFFICE.

SAMUEL GOLDBERG, OF NEW YORK, N. Y., ASSIGNOR TO UNIVERSAL FIXTURE CORPORATION, OF NEW YORK, N. Y., A CORPORATION OF NEW YORK.

DISPLAY FIXTURE.

Application filed February 23, 1921. Serial No. 447,056.

To all whom it may concern:

Be it known that I, SAMUEL GOLDBERG, a citizen of the United States, and resident of the borough of Manhattan, in the city, 5 county, and State of New York, have invented certain new and useful Improvements in Display Fixtures, of which the following is a specification.

This invention relates to improvements in 10 display fixtures, and has for its objects to provide a simple and inexpensive fixture of compact construction for effectively displaying books, magazines, picture post cards, and other articles, and to provide a revolving 15 display fixture constructed of parts of light weight which may be very easily assembled and taken apart.

In the drawings, Fig. 1 is a side elevation 20 of the fixture;

Fig. 2 a perspective view of one of the 25 removable rows of article-holding frames;

Fig. 3 a horizontal section on the line III-III of Fig. 1; and

Fig. 4 a vertical section on the line 25 IV-IV of Fig. 3, only one row of article-holding frames being shown.

The base of the fixture comprises a light metal casting having three supporting legs 1 of channel form extending radially outward and downward from a central hub 2 provided with a socket or standard-receiving 30 passage 3. A tubular metal standard 4 has its lower end detachably and non-rotatably held in socket 3, said standard being locked in the socket by a set screw 5 threaded through the hub portion 2 of the base. The lower revolving head of the fixture comprises a light metal casting having a hub portion 6 loose on standard 4 and connected by radial arms 7 with a flat annular rim 8. The lower end of hub 6 of this head rests on the upper end of the central portion or hub 2 of the base. The upper revolving head comprises a sheet metal disk 9 loosely 45 mounted on standard 4 and preferably having its periphery pressed downwardly to form a stiffening rim 10.

Several vertical rows of three-sided channel frames are detachably connected to the 50 two revolving heads, each vertical row of frames lying in a plane tangential to a circle described about the standard 4. Each arti-

cle-holding frame is formed of a single piece of sheet metal and comprises a top wall 11, a bottom wall 12, and one vertical 55 side wall 13. The top wall of each frame is provided with depending article-retaining flanges 14 along its inner and outer edges, the bottom wall is provided with up-standing edge flanges 15, and the side wall 16 60 13 is provided with inwardly extending edge flanges 16. The abutting walls 11 and 12 of all of the frames in each row are spot-welded to each other, and two vertical rods 17 and 18 are spot-welded to the inner face 65 of each row of frames. Rod 17 is welded to the flanges 14 and 15 at the inner face of each frame, adjacent the open side of the frame, and rod 18 is welded to the flange 16 at the inner face of each frame. 70

The upper ends of rods 17 and 18 project above the top wall of the uppermost frame in the row and engage in apertures in the upper head 9. The lower ends of the rods project below the bottom wall of the lowermost frame in the row and engage in apertures in rim 8 of the lower head. The apertures in which rods 17 engage are located adjacent the outer edge of the rim, and the apertures in which rods 18 engage 80 are located adjacent the inner edge of the rim, so that the lowermost frame is seated on the rim 8 of the lower head throughout the major portion of the area of its bottom wall. The rod-receiving apertures in the heads are 85 so located that each row of frames lies in a plane tangential to a circle described about the axis of rotation of the series of rows of frames, and so that the side walls 13 of the frames in each row are located wholly inside the open sides of the frames in the next row, the walls 13 of one row of frames being overlapped by the next row of frames. This arrangement permits the assembly of a large number of vertical rows of frames 95 between heads of small diameter without obscuring any part of the open outer faces of the frames.

The upper head 9 is held clamped upon the top walls of the upper frames in the several rows by means of a collar 19 detachably locked on standard 4 by a set screw 20 and engaging the upper face of the head 9. It will be obvious that by loosening the col-

lar 19 and lifting head 9, the several rows of rigidly connected pockets may be readily removed. It will also be obvious that the two revolving heads may be readily slipped on and off the standard 4, and that the standard may be readily disconnected from the base.

What I claim is:

1. A revolving display fixture comprising a base, a vertical standard, means for detachably and non-rotatably connecting the standard with the base, a lower revolving head detachably and rotatably mounted on the standard and resting on the base, an upper revolving head detachably and rotatably mounted on the standard, a collar detachably locked on the standard and engaging the upper side of the upper head, a plurality of vertical rows of three-sided channel frames, the frames in each row being rigidly connected and having their open sides overlapping the closed sides of the frames in the next row, and means forming independent separable connections between each row of frames and the two revolving heads.

2. A revolving display fixture comprising a base, a vertical standard, means for detachably and non-rotatably connecting the standard with the base, a lower revolving head detachably and rotatably mounted on the standard and resting on the base, an upper revolving head detachably and rotatably mounted on the standard, a collar detachably locked on the standard and engaging the upper side of the upper head, a plurality of vertical rows of three-sided sheet metal channel frames extending between the heads in different vertical planes all tangential to a circle described about the standard, the open sides of all of the frames facing in the same direction around the fixture and all of the frames in each row being rigidly connected together, and means for detachably connecting each row of frames to both revolving heads.

3. A revolving display fixture comprising a base, a vertical standard, means for detachable and non-rotatably connecting the standard with the base, a lower revolving head detachably and rotatably mounted on the standard and resting on the base, an upper revolving head detachably and rotatably mounted on the standard, a collar detachably locked on the standard and engaging the upper side of the upper head, a plurality of vertical rows of three-sided sheet metal channel frames extending between the heads in different vertical planes all tangential to a circle described about the standard, the open sides of all of the frames facing in the same direction around the fixture and the top wall of each frame being welded to the bottom wall of the next higher frame, and a pair of vertically extending metal rods welded to the inner faces of each row of

frames, said heads having apertures therein in which the ends of the rods engage.

4. A display fixture comprising a base, a vertical standard held to the base, a pair of vertically spaced heads detachably held to the standard, and a plurality of vertical rows of three-sided channel frames detachably clamped between the heads, said rows of frames lying in different vertical planes all of which are tangential to a circle described about the standard, the open sides of all the frames facing in the same direction around the fixture and all of the pockets in each row being rigidly connected together, the open sides of the frames in each row being located adjacent to and outside of the closed vertical sides of the frames in the next adjacent row.

5. A display fixture comprising a base, a vertical standard held to the base, a pair of vertically spaced circular heads detachably and rotatably mounted on the standard, a plurality of vertical rows of three-sided channel frames extending between the heads, the frames in each row being rigidly secured to each other and having their open sides at the same edge of the row, and means for detachably connecting the rows of frames to the heads to rotate therewith, with the closed vertical sides of the frames in each row overlapped by the open vertical sides of the frames in an adjacent row and the open sides of the rows of frames located outside of and substantially tangential to the perimeters of said heads.

6. A display fixture comprising a base, a vertical standard held to the base, a pair of vertically spaced heads detachably and rotatably mounted on the standard, a plurality of vertical rows of three-sided channel frames clamped between the heads, the frames in each row being rigidly secured to each other and having their open sides at the same edge of the row, and a pair of vertical reinforcing rods secured to each row of frames, said heads having apertures in which the ends of the rods engage and said apertures being so located that each row of frames lies in a plane tangential to a circle described about the standard.

7. A display fixture comprising an upstanding support, a circular series of rigid article-holding pockets arranged around said support in independently removable units with the pockets in each unit rigidly connected, said series of pockets being arranged in vertical rows with the entrance openings of each row along one vertical edge of the row outside of the vertical plane of the outer face of the adjacent row, a pair of heads mounted on the support and capable of relative vertical movement longitudinally of the support, one pocket of each row being seated on the lower one of said heads, and interlocking connections between said heads

and each removable unit of said series of pockets separable by relative vertical movement between the heads.

8. A display fixture comprising an up-
5 standing support, a circular series of article-
holding pockets arranged around said sup-
port in independently removable rigid units
of connected pockets, said series of pockets
being arranged in vertical rows with the
10 entrance openings of each row along the
same vertical edge of the row outside of the
vertical plane of the outer face of the ad-
jacent row, a pair of vertically spaced heads
15 rotatably mounted on the support and
capable of relative vertical movement longi-
tudinally of the support, interlocking connec-
tions between said heads and the several
removable units of said series of pockets for
20 holding the series of pockets to rotate with
the heads, said connections being separable

by relative vertical movement between the
heads, and means for releasably holding the
heads against relative vertical movement.

9. A display fixture comprising a pair of
vertically spaced heads, means for support-
ing the heads for rotary and relative vertical
movements, vertical rows of article-holding
pockets arranged around the axis of rota-
tion of the heads with one pocket of each
row resting on the lower head, the pockets 30
in each row being connected to form an inde-
pendent rigid unit, vertically separable in-
terlocking connections between the heads and
rows of pockets for holding the pockets and
heads to rotate as a unit, and means for 35
releasably holding said heads against rela-
tive vertical movement.

In testimony whereof I hereunto affix my
signature.

SAMUEL GOLDBERG.
